UNITED STATES PATENT OFFICE.

HENRY S. SATTERLEE, OF NEW YORK, N. Y.

FLEXIBLE CORE FOR MOLDING.

Application filed July 17, 1924. Serial No. 726,502.

To all whom it may concern:

Be it known that I, HENRY S. SATTERLEE, a citizen of the United States, and a resident of New York city, county and State of New York, have invented an Improvement in Flexible Cores for Molding, of which the following is a specification.

My invention relates to cores used in the process of molding and has to do specifically with flexible cores for the molding of spiral or curved cavities in one piece or single block castings.

Heretofore the formation of a curved or spiral cavity in a casting has necessitated such casting being made in two or more parts and then assembled. Particularly in the case of non-metallic substances the probabilities of uneven surfaces and inaccurate wall jointures are greatly increased in a multi-part casting.

The use of my core insures cavities perfect in form and surface and at a great reduction in cost and simplicity of production.

My invention may best be understood by reference to the following specification and the drawings which form part of it.

Figure 1 is a plan view of a core for forming a logarithmic spiral cavity.

Figure 2 shows the core placed in a mold and having certain variations.

In the drawings, 1 is the core proper made of a flexible or resilient material, or compound, such as rubber, gelatine or the like, and which can be initially formed in a fluid or plastic state.

At 2 is a traction member preferably of braided rope having a handle or grip 3 at its free end. This traction member may have a uniform diameter throughout its length and function well, but I prefer this to have a gradually diminishing diameter toward the smaller end of the spiral as I have shown in the drawing.

Disposed along and fixed to the rope 2 are fins 4, which correspond in number and spacing to the particular type and size of core in which they are applied. These fins are preferably made of a light metal and at their outer ends are wire stays 5 joining those outer ends with the member 2.

Consequently these fins 4 are held so that they slant in the direction of the pull—that

is, toward the handle 3. The amount of this slant for best results I find to be when the fins 4 make angles with their radius vectors such as O R of from 10° to 30° .

As the body of the core decreases toward the small end of the spiral, the fins 4 also decrease until, toward the very end they may be replaced by knots in the rope or traction member. Such knots are shown at 7.

It will be noted that these fins 4 determine the position of the rope 2 and its location is such as to bring the fins 4 relatively near the outer boundary of the core 1.

The fins 6 on the lower side of the rope 2 and having stays 8 also slant in the same direction as the fins 4. The degree of slant of these fins need not be the same as that of the fins 4, nor is it necessary that they form the same angle with their respective radius vectors.

Figure 2 illustrates my core 1 placed in a flask 9 ready for pouring. The body of the core 1 may be supported in any conventional manner such as chaplets. The larger extremity of the core may be supported, as at 10, by suitable means such as a clamp (not shown).

At the small extremity of the horn I show a metallic piece 11 which, in this instance, is a hollow stem for the application of a reproducing or loud speaking unit.

This stem 11 fits closely over the small end of the spiral core 1 and is held there by passing the end of rope 2 through stem 11 and binding it there by means such as pin 12. The stem 11 passing through the flask 9, forms a support for the small end of the core 1.

If so desired, the larger end of the core 1 may be supported by a tapered pin 13 which passes through the flask 9 into the core 1 as shown.

From the foregoing it is clear that my core may be of such a form of spiral or curve that it may be all in one plane, or it may be in several planes. I am not limited beyond the elasticity of the core material.

The operation of my invention is as follows:

The core 1 is greased or covered with lubricant and placed in the flask as described and shown in Figure 2.

The material to form the casting such as a gypsum cement, coverite or other substance, is poured in the flask or otherwise molded about the core and allowed to set. 5 Whatever taper pins were used to support the core are then withdrawn and the openings left by them are filled with the casting material. If chaplets are used for support these are previously made of the casting material and are left embedded in the casting when the core is withdrawn.

If a stem such as 11 in Figure 2 is used, the pin 12 is withdrawn at the time the other pins or chaplets are taken out so that 15 the core and stem will separate upon withdrawal of the former.

The main core 1 is now ready to be removed. This is done by exerting a moderate tension in the handle 3 to overcome the 20 initial resistance of the core after which it can be pulled out without effort, leaving a perfectly smooth, accurately formed cavity. Also where the stem 11 is used, the passage of that stem will register perfectly with the 25 spiral cavity to form a continuous and smooth passage, and the stem will be held solidly in the casting after the core is removed.

The method of removing the flexible core 30 1 involves certain factors which are found only in my invention.

The act of traction upon the handle 3 is transmitted through the member 2 and the stays 5 and 8 to the fins 4 and 6, and distribute the traction effort throughout the 35 length of the core. These fins, particularly those at 4, exert a tangential pull upon the core. This, combined with the elastic properties of the core substance, operates 40 to first free the outer surface of the core from the casting and to pull the core slightly forward and permit the dislodgment of the inner border. This first small movement not only frees the core from the casting but 45 permits the gradual entrance of air between the surfaces so that there is no vacuum adherence.

The core once started, is withdrawn without effort; the flexibility of its material permitting 50 it to pass the curves in the casting without trouble and leaving a smooth, uniform passage.

In being removed from the casting, the core naturally undergoes a certain amount 55 of distortion of its curves. Nevertheless, I have found that, when properly constructed, a core of this nature may be used an indefinite number of times for it resumes its original shape in all respects and suffers 60 no permanent set from use.

While I have preferred to explain my invention by reference to the formation of cavities of a spiral form, it is clear that I may make any form of curved cavity and

the amount of draught allotted to the core 65 need be no greater than is customarily used in the art of molding.

Therefore I desire to include in my claims the full breadth of my invention.

I claim:

1. A flexible core having a curved body, 70 a traction member therein and a plurality of transverse elements disposed along and fixed to said traction member.

2. A flexible core having a curved body, 75 a traction member therein, a plurality of transverse elements disposed along and fixed to said traction member, and stay members connecting the transverse elements with the traction member.

3. A flexible core having a curved body, the cross sectional area of which gradually decreases from one end toward the other, a traction member in said body and extending the full length thereof, a plurality of fins 85 disposed along said traction member and held at a predetermined angle thereto by stay members.

4. A flexible core having a tapered body 90 of spiral form, a traction member within said body so positioned as to be relatively closer to the outer border of said spiral body than it is to the inner border, traction distributing elements disposed along and fixed to said traction member and located transversely thereof, said traction distributing elements being bent at a predetermined angle in the direction of traction and held thereto by stay members extending between the traction distributing elements and the 100 traction member.

5. A flexible core having a curved body, a traction member therein having transverse elements disposed along and fixed to said traction member in such numbers and of 105 such dimensions as to distribute the traction effort throughout the length of said core.

6. The method of molding curved cavities which comprises pouring casting material around a solid flexible core of the curvature 110 desired, and finally withdrawing said core from the casting material.

7. The method of molding curved cavities which comprises pouring casting material around a solid flexible core of the curvature 115 desired, then freeing said core from its initial position to permit air to enter the casting and finally withdrawing the core.

8. The method of molding curved cavities which comprises pouring casting material 120 around a flexible core, then freeing the core from its initial position by tangential force exerted upon the core, and finally withdrawing the core.

In testimony whereof, I have signed my 125 name to this specification this 12th day of July.

HENRY S. SATTERLEE.
